UNITED STATES PATENT OFFICE

160,349

TABLE TOP AIR CIRCULATING UNIT

Ottis A. Sutton, Wichita, Kans., assignor to The
O. A. Sutton Corporation, Inc., Wichita, Kans.,
a corporation of Kansas

Application March 24, 1950, Serial No. 8,755

Term of patent 14 years

(Cl. D26—7)

To all whom it may concern:

Be it known that I, Ottis A. Sutton, a citizen of the United States of America, residing at Wichita, county of Sedgwick, State of Kansas, have invented a new, original, and ornamental Design for a Table Top Air Circulating Unit, of which the following is a specification, reference being had to the accompanying drawing, forming part hereof.

Fig. 1 is a view in elevation of the air circulating unit, showing my new design with the fan directed vertically upward;

Fig. 2 is a view in elevation with the air circulating unit rotated a few degrees clockwise from the position of Fig. 1 and with the fan directed laterally at an angle to the horizontal;

Fig. 3 is a top plan view of the unit; and

Fig. 4 is a view in elevation with the unit rotated clockwise ninety degrees from the position of Fig. 2 and the fan unit directed horizontally.

I claim:

The ornamental design for a table top air circulating unit, as shown.

OTTIS A. SUTTON.
